HOSE WASHING MACHINE

Kenneth G. Sedgwick, Cavour, Wis.; dedicated to
the free use of the People of the United States
of America

Application June 14, 1938, Serial No. 213,591

4 Claims. (Cl. 15—88)

(Granted under the act of March 3, 1883, as
amended April 30, 1928; 370 O. G. 757)

This application is made under the act of
March 3, 1883, as amended by the act of April 30,
1928, and the invention herein described, if pat-
ented, may be manufactured and used by or for
5 the Government of the United States of America
for governmental purposes without the payment
to me of any royalty thereon.

I hereby dedicate the invention herein de-
scribed to the free use of the people of the United
10 States of America to take effect on the granting
of a patent to me.

This invention relates to a machine for wash-
ing hose, especially hose of the collapsible flat
linen type, such as that used for fire extinguis-
15 hing purposes.

One of the objects of this invention is to pro-
vide such a machine that will automatically wash
all sides of the hose at one time as it is fed
20 through it, wetting the hose as it approaches the
washing operation, and rinsing it after it leaves
the washing operation.

The following description considered together
with the accompanying drawings will disclose
this invention more fully, its construction and
25 operation of parts, and further objects and ad-
vantages thereof will be apparent.

In the drawings:

Figure 1 is a side elevational view; and

Figure 2 is a plan view of this invention.

30 Figure 3 is a fragmentary side elevational view
of the horizontal reciprocating brushes in wash-
ing position.

Figure 4 is an end view of Figure 1 from the
line 4—4.

35 Figure 5 is an enlarged end sectional view along
the line 5—5 of Figure 1.

Figure 6 is a schematic diagram of the linkage
employed to reciprocate the brushes.

Referring with more particularity to the draw-
ings in which like numerals designate like parts, a
40 lower guide bar 8 is bracketed to a suitable frame
7 and a lower brush carrier 9 is slidably mounted
on said bar by means of sleeve brackets 10 and
11. One, two or more brushes 12 are removably
45 secured on said brush carrier 9 with their bristles
extending upward. Metal anti-friction plates
13, 13 on said brush carrier and similar plates
14, 14 on said bar 8 contacting said plates 13, 13
may be provided to reduce sliding friction. Also
50 anti-friction plates 14a, 14a may be provided to
reduce friction between the brackets 10 and 11,
and the bar 8. The upper brush bar 15 is hinged-
ly mounted on the frame at 16 and upper brush
carrier 17 is slidably mounted thereon (similar
55 to the manner in which the lower brush carrier

9 is mounted on the lower brush bar 8) by means
of sliding brackets 18, 18 beneath said member 15.
The upper brushes 19, 19 are secured beneath
said brush carrier 17, bristles down. Plates 20, 20
secured to the bar 15, plates 21, 21 secured to the
5 upper brush carrier 17 and plates 22, 22 secured
to the member 15 between the sleeve brackets 18
and 29 are provided to reduce friction. As shown
by the drawings, the bristles of the brushes face
each other.

Said brushes are oppositely reciprocated by
means of a lever 23 fulcrumed to a bracket 24 se-
cured to the frame of the machine. One end of
each of the links 25 and 26 are pivotally con-
nected at points 27 and 28 to the lever 23 sub-
stantially equidistant from the said fulcrum.
The other end of link 25 is pivotally connected
10 to the bracket 29 of the upper brush carrier 17
and the other end of the link 26 is pivotally con-
nected to a bracket 11 of the lower brush carrier
15. A connecting rod 31 is disposed between the
lower end of the lever 23 at 32 and a crank arm
33. Said crank arm is attached to the crank
shaft 34 which is rotatably mounted in bearings
conveniently disposed in the lower part of the
20 frame of the machine. Said crank shaft is ac-
tuated by a motor 35 fixed to the base of the ma-
chine. Power is delivered from a grooved pulley
36 fixed to the crank shaft 34 by means of a friction
V-belt 37, substantially as shown. A trough 38
25 is mounted on the frame of the machine forward
of the brushes and another trough 39 is similarly
mounted rearward of said brushes through both
of which the hose to be washed slides.

In Figure 1 the upper brush assembly, consist-
ing of the bar 15 and parts appurtenant thereto,
is shown in dotted lines in its open position, re-
volved about its hinged point 16. When the ma-
chine is in operation this upper brush assembly
40 must be held firmly against the top of the hose
being washed and for this purpose a hook 40
with a handle extension 41 is swiveled to a
bracket 42 mounted on the rearward end of the
upper brush bar 15. Said hook 40 is adapted to
45 catch under a guide bracket 43 fixed to the frame
of the machine. The handle 41 when the ma-
chine is operated may be held in position by any
suitable means such as a catch 44.

A water pipe line 45 is disposed across the
50 top of the outer sides of the troughs 38 and 39,
bridging the space therebetween, and thence
around the opposite side of said troughs, sub-
stantially as shown. The water intake connec-
tion and valve assembly 46 is preferably posi-
55

tioned near or in the U-bend in the pipe. The pipe is positioned as closely as possible to the brushes and is provided with apertures at optimum points to permit sprays of water to play 5 on the brushes and upon the hose as it passes through said troughs.

In order to provide for the cleansing of the sides of the hose which may escape the action of the horizontal brushes above mentioned, vertical brushes 47 and 48 are utilized, the vertical brush 47 being disposed on the bracket 49 fixed to the lower brush carrier 9 and the vertical brush 48 is mounted on a bracket 38 fixed to the upper brush carrier 17. The said vertical brushes 47 10 and 48 are mounted in such a way that they exert a pressure contact upon the sides of the hose as it passes through the machine. If desired a shield 50 may be bracketed to the frame 15 of the machine to shield the motor from any water and dirt that may be thrown out of the machine.

The operation of this invention is as follows: The motor 35 is started and water is delivered through the pipe line 45 by opening the valve 25 46. The motor supplies power by means of the V-belt 37 to the pulley 36 which in turn rotates the crank shaft 34 and thus the crank arm 33 revolves carrying with it the link 31 connected to the end of the lever 23. This causes 30 lever 23 to oscillate about its fulcrum, carrying with it the links 25 and 26 and in turn the brushes 19 and 12, respectively, are thus oppositely reciprocated. The upper brush assembly is then elevated in substantially the position shown by 35 the dotted lines in Figure 1, the brushes being in motion meanwhile. The fact that this may be done with the machine running permits continuous operation, avoiding the necessity of stopping the machine while hose is being placed in or removed from it. The hose 51 to be washed is 40 disposed lengthwise from the trough 38 over the brushes 12 and the trough 39. It is immaterial in which direction the hose is fed. This feeding is accomplished by operators stationed at the 45 ends of the machine near the said troughs. The upper brush assembly is then lowered and fixed in position by means of the hook 40 which is held in position by catch 44, as above mentioned. The hose is then drawn through the machine by hand

by one of the operators. The water flowing through the pipe line 45 escapes through the holes provided thus spraying water upon the brushes and upon those parts of the hose passing through the troughs 38 and 39. The brushes 5 being firmly pressed against the surface of the hose and being in motion as described above, scrub the dirt from the hose as it is drawn between them.

Having thus described my invention, I claim: 10

1. A hose washing machine comprising upper and lower sets of brushes slidably mounted on horizontal bars, one of said bars being rigidly secured to the frame of the machine and the other bar being hingedly mounted on the frame 15 of the machine directly above the rigidly secured bar, each of said sets of brushes consisting of horizontally and vertically disposed brushes, and means for oppositely reciprocating said sets of brushes.

2. A hose washing machine comprising upper and lower sets of brushes slidably mounted on horizontal bars, one of said bars being rigidly secured to the frame of the machine and the other bar being hingedly mounted on the frame 25 of the machine directly above the rigidly secured bar, and means for oppositely reciprocating said brushes on said bars.

3. A hose washing machine comprising upper and lower sets of brushes slidably mounted on 30 horizontal bars, one of said bars being rigidly secured to the frame of the machine and the other bar being hingedly mounted on the frame of the machine directly above the rigidly secured bar, and a motor and a kinematic linkage system 35 for oppositely reciprocating said brushes.

4. A hose washing machine defined by claim 3 in which the kinematic linkage system comprises a lever vertically fulcrumed to the frame of the machine, a link connected between a point above the fulcrum of said lever and a bracket fixed to 40 the upper brush set, another link connected between a bracket fixed to the lower brush set and a point on said lever below the fulcrum, a crank arm secured to a rotatably mounted shaft adapted to be actuated by the motor, and a connecting 45 rod disposed between said crank arm and said lever at the point below the fulcrum.

KENNETH G. SEDGWICK.
